Primary Examiner — Catherine A Tuttle(74) *Attorney, Agent, or Firm* — Lambert & Associates; Gary E. Lambert; David J. Connaughton, Jr.(57) **CLAIM**

The ornamental design for the hockey training device, as shown and described.

DESCRIPTION

FIG. 1 is a perspective top view of the hockey training device, which embodies my design;

FIG. 2 is a perspective bottom view thereof;

FIG. 3 is a bottom plan view thereof;

FIG. 4 is a top plan view thereof;

FIG. 5 is a left side view thereof;

FIG. 6 is a right side view thereof;

FIG. 7 is a rear view thereof; and,

FIG. 8 is a front view thereof.
